Patented Apr. 3, 1923.

UNITED STATES PATENT OFFICE.

BENJAMIN COUSINS, OF SLICK, OKLAHOMA.

CEMENTING DUMPER.

Application filed December 8, 1921. Serial No. 521,063.

To all whom it may concern:

Be it known that I, BENJAMIN COUSINS, a citizen of the United States, residing at Slick, in the county of Creek and State of Oklahoma, have invented certain new and useful Improvements in Cementing Dumpers; and I do hereby declare the following to be a full, clear, and exact description of the invention, such as will enable others skilled in the art to which it appertains to make and use the same.

My invention relates to a cementing dumper for placing mud or cement of the desired consistency in the bottom of an oil well for the purpose of preventing water from entering the well. Bailers or other devices at present employed in the "mudding in" and cementing of oil wells are slow and uncertain in unloading, with the result that the placing of the mud or cement is only effected with a great expenditure of time and labor.

The object of the present invention is to provide a simple, strong and durable cementing dumper by which the cementing mixture may be easily, quickly and certainly placed in the well at the desired point.

A principal feature of the invention, generally stated, consists in constructing a cementing dumper with a tube having a delivery opening through the lower end thereof, and in providing for said delivery opening a closure which is capable of bodily movement in the direction of length of said tube, means adapted to be suspended from a bailing line or the like being releasably connected to the closure for maintaining the latter in closed relation to the tube, and means also being provided for suspending the said closure from the tube when the closure is in open position.

A further feature of the invention consists in constructing a cementing dumper with a tube having a delivery opening through the lower end thereof, and in providing a movable closure for the delivery opening, latching means detachably connected to the closure and adapted to be suspended from a bailing line being employed for maintaining the said closure in closed relation to the tube, the said closure when in such position being adapted to carry the entire weight of the tube.

Another feature of the invention consists in constructing a cementing dumper with a tube having a delivery opening, a movable

closure for said opening, a stem connected to said closure and extending upwardly within the tube, means releasably connected to said stem for suspending the latter from a bailing line, and an automatically operated device for preventing accidental relatching of the closure in closed position after it has moved to open position for permitting discharge of the contents of the dumper.

Other features of the invention, residing in particular combinations of parts and in details of the elements of the mechanism, will hereinafter appear.

In the drawings chosen for the purpose of illustrating the invention, the scope whereof is pointed out in the claims.

Figure 1 is a view, partly in elevation and partly in vertical section, of a cementing dumper embodying the invention, parts being broken away and the elements of the device being shown in the relations they occupy when the dumper is loaded and being lowered into the well.

Figure 2 is a view corresponding to Fig. 1, but illustrating the positions assumed by the parts to allow the discharge of the cementing mixture.

In the drawings, 1 indicates a tube or containing body for receiving the mud or cement. The entire lower end of the tube 1 is preferably open to afford a large delivery opening 2 through which the cement may discharge without obstruction. Near its lower end the said tube is provided with a downwardly facing seat or shoulder 3 for engaging the upper surface of a valve plate or closure 4 forming a movable bottom for the tube. The lower portion of the tube is preferably formed externally of said seat or shoulder 3 with a shoe or flange 5 which extends below and embraces the bottom member or valve plate 4 when the latter is in closed position, the said shoe 5 preferably being fashioned separately and united to said tube 1 by spot welding or in other suitable manner. As will be perceived, the shoe 5 not only serves to protect the seat 3 and closure 4 from defacement and injury but it also serves to guide the valve or closure 4 to proper seating engagement with the shoulder 3 and to center said valve plate when the latter is in closed position.

The closure 4, which may conveniently be coned as indicated at 6, is connected to a stem member 7 which extends upwardly within the tube 1, the upper end of said stem

preferably projecting above a V-shaped filling opening 8 which may be advantageously provided at one side of the upper end of the tube. The closure or bottom 4 is preferably 5 connected to the stem 7 in such manner that the said closure when in open position may be capable of a universal tilting or tipping movement, thus allowing it to yield in any direction in response to the pressure of the 10 cementing mixture that is being discharged from the dumper. A simple mode of forming such a connection between the closure 4 and the stem 7 is to provide the said closure with a centrally disposed eye 9 which 15 interlocks with an eye 10 at the lower end of the stem member 7.

Secured to and projecting above the upper end of the tube 1 is a bail 11, the lower ends of the arms of which are preferably 20 located within the tube and secured to the latter by rivets 12. The interior of the tube 1 between the shoulder or valve seat 3 and the lower ends of the bail 11 is smooth or 25 free from projections, thus allowing free discharge of the load from the tube or shell 1.

Extending transversely of the tube and preferably connecting the arms of the bail 11 above the upper end of said tube is a 30 hanger bar 13 from which the stem 7 and the valve member or closure 4 carried thereby are suspended when the said valve is in open position. The hanger bar 13 passes through an eye 14 at the upper end of the 35 valve stem 7, the eye being elongated so as to permit the valve plate or closure 4 to move bodily downward and away from the lower end of the tube 1. The movable stem 7 is also fashioned at its upper end with another eye 15 which cooperates with certain 40 latching means now to be described, and through which the closure or valve plate 4 is releasably maintained in closed position.

The latching mechanism for maintaining 45 the closure or bottom plate 4 in closed position while the dumper is being lowered in the well is preferably a hook member 16 having an elongated eye 17 through which the bail 11 passes and which is adapted to 50 be secured to a bailing line or cable (not shown). The lower end of the member 16 is formed as a hook or spur 18 which is integrally connected to the eye 17 by the stem portion 19. Upon the stem 19 is slidably 55 mounted an annular sleeve 20 which, as illustrated in Fig. 2, is adapted under the influence of gravity to assume a position preventing the eye 15 at the upper end of the stem 7 from accidentally engaging with 60 the hook 18 after the bottom 4 of the dumper has moved to open position. As shown in Fig. 1, the hook or spur 18 extends through the eye 15 at the upper end of the valve stem when the valve or closure 4 is in closed 65 position.

Assuming the dumper to be suspended from a bailing line attached to the eye 17 at the upper end of the hook member 16, the several parts of the mechanism will occupy the positions shown in Fig. 1 when the 70 cementing material is being lowered into the well, it being noted that the entire weight of the tube 1 and of the cementing material within the tube is transferred from the bottom 4 to the stem 7 and thence through the 75 hook member 16 to the bailing line. When the dumper rests on the bottom of the well the tension of the bailing line is released from the hook member 16 and the latter thereupon moves downwardly with respect 80 to the valve stem 7, thereby causing the hook or spur 18 to be disengaged from the eye 15 at the upper end of the said stem 7. The unlatching of the stem 7 from the hook 18 allows the dumper bottom 4 to move 85 away from the bottom of the tube 1, thus uncovering the delivery opening 2 in the bottom of the dumper and allowing the cementing material to be discharged. When the eye 15 of the valve stem has been disengaged from the hook the sliding weight 20, which has been forced upwardly to permit these parts to be disconnected, slides downwardly upon the stem portion 19 of the hook member so as to prevent the eye 15 90 from accidentally reassuming latched relation with the member 16. When the closure 4 is in open position the stem 7 by which it is suspended is supported upon the hanger bar 13. The dumper having once been 95 opened within the well remains open until it is drawn to the top of the hole and re-latched for recharging.

If it is desired to unload the dumper at an intermediate point in the well all that is 100 necessary to do is to plunge the device quickly down the hole and stop it suddenly at the desired point of unloading. This causes the dumper to rebound, thereby relieving the tension of the bailing line and 105 effecting an unlatching of the valve plate or closure 4 in the manner heretofore described.

I claim:—

1. A cementing dumper comprising a tube 115 having a delivery opening at the lower end thereof, a movable bottom for said tube, said bottom being capable of bodily movement in the direction of length of said tube, means detachably connected to said bottom for maintaining the latter in closed relation to said tube, said means being adapted to be suspended from a bailing line and being adapted to be operatively detached from said bottom to permit the latter to assume an open position, and means for suspending said bottom from said tube.

2. A cementing dumper comprising a tube having a delivery opening through the lower end thereof, a movable bottom for said tube,

movable means extending within said tube for supporting said bottom in closed position and also in open position, releasable means for supporting said movable means when said bottom is in closed position, and

means independent of said releasable means for supporting said movable means from said tube when said bottom is in open position.

10 3. A cementing dumper comprising a tube having a delivery opening through the lower end thereof, a movable bottom for said tube, movable means extending within said tube for supporting said bottom in closed position and also in open position, latching means for supporting said movable means when said bottom is closed, and means for supporting said movable means when said bottom is open, said bottom being movably connected to said movable means.

15 4. A cementing dumper comprising a tube having a delivery opening through the lower end thereof, a bottom for said tube, said bottom being bodily movable downwardly to uncover said delivery opening, and means on said tube for centering said bottom in closed position, said means extending below and embracing said bottom when the latter is in closed position.

20 5. A cementing dumper comprising a tube having a delivery opening through the lower end thereof, a movable bottom for said tube, and means for releasably maintaining said bottom in closed position, said tube being provided with a downwardly facing seat for engaging said bottom and having a shoe portion external to said seat extending below and embracing said bottom when the latter is in closed position and serving to guide 25 said bottom to closed position.

30 6. A cementing bailer comprising a tube having a delivery opening through the lower end thereof and provided with a bail at its upper end, a movable bottom for said tube, means for releasably maintaining said bottom in closed position, said tube being provided with a downwardly facing seat for said bottom and its interior between said seat and said bail being smooth, and means 35 extending below said seat for guiding said bottom to closed position.

40 7. A cementing dumper comprising a tube having a delivery opening, a movable closure for said opening, a stem connected to said closure and extending within said tube, means operatively releasable from said stem for connecting the latter to a bailing line, and means for supporting said stem from said tube when said closure is in open position, 45 said closure being connected to said stem only.

45 8. A cementing dumper comprising a tube having a delivery opening, a movable closure for said opening, a bail mounted on said tube, a hook member movably mounted on

said bail, a stem connected to said closure and adapted to be releasably connected to said hook member, and means for supporting said stem when the latter is released from said hook member.

70 9. A cementing dumper comprising a tube having a delivery opening, a movable closure for said opening, a stem movably connected to said closure, a bail secured to said tube, means movably mounted on said bail for releasably supporting said stem to maintain said closure in closed position, and means for supporting said stem when said closure is in open position.

75 10. A cementing dumper comprising a tube having a delivery opening through the lower end thereof, a movable closure for said opening, a bail secured to said tube, a stem connected to said closure and extending upwardly therefrom within said tube, a hanger 80 bar extending transversely of said tube and adapted to support said stem, a hook member movably mounted on said bail and adapted to support said stem, said stem being provided with an eye adapted to receive said 85 hook member, and said hook member and stem being adapted to be disengaged by a movement of said hook member toward said closure, and means movably mounted on said hook member for preventing accidental re- 90 engagement of said hook member and eye.

95 11. A cementing dumper comprising a tube having a delivery opening, a movable closure for said opening, a stem connected to said closure and extending upwardly 100 within said tube, means releasably connected to said stem for suspending the latter from a bailing line, and a device movable with respect to said means for preventing accidental reconnection of said stem and said 105 means.

110 12. A cementing dumper comprising a tube having a filling opening and a delivery opening, a movable closure for said delivery opening, a stem connected to said closure and extending upwardly through said tube and projecting above said filling opening, a bail secured to and extending above the upper end of said tube, a hook member movably mounted on said bail and adapted releasably 115 to support said stem, said hook member and stem being relatively movable to effect their disconnection, a sleeve mounted on said hook member to prevent accidental reconnection of said stem and hook member, and means for supporting said stem when it is released from said hook member.

120 13. A cementing dumper comprising a tube having a delivery opening through the lower end thereof, a movable bottom for said tube, and latching means detachably connected to said bottom and adapted to be suspended from a bailing line for maintaining said bottom in closed relation to said tube, said bottom when in open position be- 125 130

ing released from said latching means and when in closed position being adapted to support the entire weight of said tube.

14. A cementing dumper comprising a tube having a delivery opening through the lower end thereof, a movable bottom for said tube, and means adapted to be suspended from a bail line for maintaining said bottom in closed relation to said tube, said tube having a portion of greater diameter than the interior of said tube above said movable bottom which extends below and embraces said bottom when the latter is in closed position, and said bottom when in closed position being adapted to support the entire weight of said tube.

15. A cementing dumper comprising a tube having a delivery opening at the lower end thereof, a movable bottom adapted to close said opening, and latching means for

maintaining said bottom in closed relation to said tube, said bottom when in open position being adapted to have a universal tipping movement, and said latching means being releasable from operative relation to 25 said bottom by a relative movement of said bottom and said latching means.

16. A cementing dumper comprising a tube having a delivery opening therein, a closure for said delivery opening, and latching means for maintaining said closure in position for closing said opening, said latching means being adapted to be released by a relative movement of said closure with respect to said tube, and said closure when 30 in open position being adapted to have a universal tipping movement.

In testimony whereof I affix my signature.

BENJAMIN COUSINS.
